Attorney

UNITED STATES PATENT OFFICE.

FRANK B. PARDEY, OF WARREN, RHODE ISLAND.

ANCHOR.

Application filed March 11, 1921. Serial No. 451,494.

To all whom it may concern:

Be it known that I, FRANK B. PARDEY, a citizen of the United States, residing at Warren, in the county of Bristol and State 5 of Rhode Island, have invented certain new and useful Improvements in Anchors, of which the following is a specification.

This invention relates to an improved anchor of the type wherein the fluke is 10 pivotally mounted in a supporting frame.

One object of the invention is to provide a device of this character wherein the parts are so constructed as to insure the fluke being brought into engaging position when 15 the anchor is drawn along the sea bottom.

Another object of the invention is to provide a device of the class described having a novel form of fluke adapted to embed itself readily in the sea bottom while at the 20 same time being readily broken out when desired.

Another object of the invention is to provide a device of this character wherein the fluke is so supported from the frame as to 25 insure its engagement with the bottom.

A further object of the invention is to provide a novel mounting for the fluke, and to so form the latter as to increase its holding power.

Other objects and advantages of the invention will be more fully set forth in the 30 detailed description to follow.

Referring to the drawings:—

Fig. 1 is a perspective view of the anchor.

Fig. 2 is a longitudinal sectional view 35 through the pivoted fluke.

Fig. 3 is a side elevational view of the anchor in normal engaging position.

Fig. 4 is a side elevational view of a 40 modified form of fluke.

Fig. 5 is a sectional view taken along the line 5—5 of Fig. 4, and,

Fig. 6 is a sectional view taken along the line 6—6 of Fig. 4.

In the embodiment of the invention illustrated in Figs. 1 to 3 of the drawings 1 45 designates generally the supporting frame which may be formed of two similar sections 2 and 3, each of which is provided

50 with a substantially straight portion 4, an outwardly bowed portion 5 and an inturned return bent portion 6. The substantially straight portions 4 of the sections 2 and 3 are positioned in contacting relation, and 55 are connected by a pin 7 passed therethrough and through the ends of a U-shaped connect-

ing link 8 which embraces the outer faces of the said straight portions and serves as a means for connecting the anchor to the cable 9. Cotter pins 10, or other suitable 60 means, may be employed for holding the pin 7 in proper position within the U-shaped connecting link 8 and thus retaining the sections in position.

The fluke 11 is provided with oppositely 65 positioned trunnions 12 located upon the median line A—B of said fluke and intermediate the toe portion 13 and the base or heel portion 14 thereof. As will be seen from the drawings the trunnions 12 are 70 located well in advance of the center of gravity C of the fluke whereby the toe portion 13 is positively drawn into engagement with the bottom when a pull is exerted upon the cable 9. While the position of the 75 trunnions as shown in the drawings, is approximately midway between the center of gravity C of the fluke and the toe portion 13, it is to be understood that the location 80 of the trunnions may be varied as desired to suit conditions which may arise in the practical application of the invention. I propose to vary the position of the trunnions between the toe portion of the anchor and the center of gravity thereof in order to 85 adapt the anchor for use in connection with the different sea bottoms and to cause the anchor to grip more or less firmly as may be desired. Cotter pins 12', or other suitable 90 means, are employed for positively holding the frame sections in position relative to the fluke, and the outwardly bowed portions 5 of the frame sections overlie the ends of the trunnions and the fastening means therefor and prevent them from 95 catching in or fouling the cable.

The return bent portions 6 of the frame are substantially parallel to each other throughout the major portion of their extent, and may be provided with a plurality 100 of registering openings 15 for receiving the trunnions 12 whereby the position of the anchor relative to the frame may be varied. It will be seen upon reference to Figs. 1 and 3 of the drawings, that a portion 16 of the frame 1 extends in the rear of the point where the fluke is pivoted to the frame by means of the trunnions 12, thus enabling the rear end portion 16 of the frame to rest upon the sea bottom where the anchor is in 105 engaging position and permit the frame to be used as a lever in breaking out or free-

ing the anchor from engagement with the bottom. This feature of the invention is very clearly shown in Fig. 3 of the drawings, where it will be seen that by a direct upward pull upon the cable 9, the frame 1 will act as a lever to raise the fluke from its embedded position.

The outwardly bowed portions 5 of the bail provide an efficient means for insuring the proper engagement by the fluke with the sea bottom, since if the anchor strikes the bottom with one of these outwardly bowed portions lowermost the weight of the fluke will cause the anchor to immediately assume the position shown in Fig. 3.

The fluke 11 is provided with a pointed toe portion 13 for facilitating its engagement with the sea bottom, and longitudinally extending strengthening ribs 17 and 18 are formed on opposite sides thereof. The heel portion 14 is provided with hollowed out portions 19 and 20 terminating at the sides in curved portions 21 and 22 respectively for engaging the surface of the bottom and drawing the toe portion into embedded position as shown in Fig. 3. The hollowed out portion lying adjacent to the sea bottom when the anchor is in operative position exerts a suction action when the anchor is in embedded position to increase the gripping action and hold the same from being accidentally broken out, while the uppermost hollowed out portion loads up with sand and mud as the anchor is drawn into its embedded position, thus serving as an additional means for preventing the anchor from becoming prematurely released.

The form of fluke shown in Figs. 4, 5 and 6 of the drawings may be substituted for that previously described, in the frame 1, if desired, and comprises a main body portion 25 provided with oppositely positioned trunnions 26 projecting from opposite sides thereof for pivotally securing the same to the supporting frame. Longitudinally extending strengthening ribs 27 and 28 are formed upon opposite sides of the body portion, and the toe portion 29 is pointed to facilitate its engagement with the bottom.

As in the fluke previously described, the trunnions are located upon the median line of the fluke, substantially midway between the toe 13 and the center of gravity C of the fluke, although I propose to vary the position of the trunnions, or pivot point of the fluke, between the toe and center of gravity to adapt the fluke for most efficient use under varying conditions.

The base or heel portion of the fluke is of skeleton formation comprising transverse webs 31, a longitudinal web 32 and an oblong border 33 integral with the transverse and longitudinal webs by which it is connected to the main body portion 25.

The opposite sides 36 of the border are

curved as shown in Figs. 5 and 6 for engaging the surface of the bottom and drawing the toe portion into embedded position therein, while the rounded ends 37 act in concert with the bowed portions 5 of the frame to insure the anchor taking such position upon the sea bottom as will enable the sides 36 to engage the bottom and assist in drawing the toe portion into the ground after the manner illustrated in Fig. 3 of the drawings.

From the above description taken in connection with the accompanying drawings it will be seen that I have provided a novel form of anchor wherein the fluke is pivoted for free movement in either of two directions relative to the supporting frame, and the manner of arranging the parts and proportioning the same is such as to insure that the anchor will under all circumstances assume such a position on the sea bottom as to properly embed itself in the bottom and be securely held against accidental release until it is desired to remove the same. While I have described the present embodiment of my invention, as disclosed in the accompanying drawings, with considerable particularity in order to make the construction and operation of the same clear to those skilled in the art, I do not desire nor intend to be limited to the precise form and arrangement of the parts as shown and described, except as the same may be included within the terms of the following claims.

What I claim is:—

1. In an anchor, a bail, and a fluke pivoted thereto for unlimited swinging movement in either direction relative to said bail.
2. In an anchor, a bail formed with inturned substantially parallel portions, and a fluke pivotally mounted in the inturned portions of the bail, for unlimited swinging movement in either direction.
3. In an anchor, a bail provided with outwardly bowed portions, and inturned substantially parallel portions, and a fluke pivotally mounted in the inturned portions of the bail for unlimited swinging movement in either of two directions.
4. In an anchor, an elongated bail provided with means intermediate its ends for pivotally supporting a fluke, and a fluke pivotally secured to said bail intermediate the ends thereof whereby a portion of the bail extends rearwardly from the point of pivotal connection of the fluke thereto to bear upon the ground and enable said bail to act as a lever for releasing said fluke from engagement with the ground.
5. In an anchor, a supporting frame, a fluke pivotally supported thereby, the said frame extending rearwardly a sufficient distance beyond the point of pivotal connection of the fluke thereto to engage the material with which the fluke is embedded and thus act as a lever for freeing the fluke.

6. In an anchor, a supporting frame, a fluke pivoted to said frame for unlimited movement in either of two directions and provided with a toe portion and a curved heel portion for drawing the toe portion into embedded position. 30
- 5 7. In an anchor, a supporting frame, a fluke pivoted to said frame for unlimited movement in either of two directions about its pivot point, said fluke being provided with a toe portion and a curved heel portion for engaging the surface of the ground and drawing the said toe portion into embedded position therein. 35
- 10 8. In an anchor, a supporting frame, a fluke pivotally supported thereby and provided with a toe portion for engaging the bottom, and a hollowed out heel portion for exerting suction upon the embedded anchor and preventing accidental breaking out of the same. 40
- 15 9. An anchor comprising a supporting frame, a fluke pivotally supported by the frame provided with a toe portion for engaging the bottom and an oblong hollowed out heel portion, the major axis of said heel portion being substantially parallel with the pivotal axis of said fluke. 45
- 20 25
10. An anchor comprising a supporting frame, a fluke pivotally supported by said frame and provided with a hollowed out heel portion and a toe portion formed integral with said heel portion and projecting therefrom substantially centrally of the interior said heel portion. 50
- 35
11. An anchor comprising a supporting frame, a fluke pivotally supported by said frame and provided with an oblong perforate shell portion and a toe portion integral with said shell and extending therefrom substantially centrally of the interior of said heel portion. 40
12. In an anchor, a supporting frame, a fluke pivotally supported by said frame and provided with an oblong perforate shell portion having a curvilinear exterior surface and a hollowed out interior, a plurality of supporting ribs connecting portions of said shell and located substantially within the interior thereof, and a toe portion integral with said ribs and projecting from the interior of said shell. 50

In testimony whereof I have affixed my signature.

FRANK B. PARDEY.
